UNITED STATES PATENT OFFICE.

THEODORE THISTLEWOOD, OF HOUSTON, DELAWARE.

ADJUSTABLE SHADE-BRACKET.

No. 826,386.

Specification of Letters Patent.

Patented July 17, 1906.

Application filed December 8, 1905. Serial No. 290,911.

To all whom it may concern:

Be it known that I, THEODORE THISTLEWOOD, a citizen of the United States, residing at Houston, in the county of Kent and State 5 of Delaware, have invented certain new and useful Improvements in Adjustable Shade-Brackets; and I do hereby declare the following to be a full, clear, and exact description of the invention, such as will enable 10 others skilled in the art to which it appertains to make and use the same.

For window-shade rollers I have produced an improved sheet-metal bracket having a pair of longitudinal slots in alinement, each 15 slot having its edge formed with teeth, the teeth of one slot being on its upper edge and the teeth of the other slot on its lower edge and the inner end of the outer slot terminating in a recess below its lower edge and the 20 inner end of the inner slot terminating in a recess above its upper edge, whereby the fastening nails or screws in the slots are caused to be engaged by the upper and lower teeth of each slot to hold the bracket to its fixed 25 adjustment and allow it to be tilted upward at its outer end to free the teeth to allow the bracket to slide to bring its recesses to register with the screw-heads to allow the bracket to be removed without removing the 30 screws. This construction renders it convenient to adjust the bracket to suit the length of the shade-roller without trouble with the fastening-nails, and the arrangement of the teeth is such as to cause them 35 to bite into the upper and the lower sides of the fastening-screws under the weight of the roller and curtain.

The accompanying drawings illustrate my improved roller-bracket in perspective in 40 Figure 1. Fig. 2 shows the bracket with the teeth of each slot in engagement with the shanks of the fastening-screws. Fig. 3 shows the bracket tilted on its fastening-screws to allow it to be moved in either direction to adjust it or to remove it when the slot-recesses 45 register with the heads of the fastening-screws. Fig. 4 is a view showing the bracket in the position to allow it to be removed from its fastening-screws.

50 The bracket is formed of a single piece of sheet metal having the angle end provided with a hole to receive the bearing-pin of the shade-roller in the usual way. The bracket has a pair of slots 1 1 in alinement, the up-

per edge of one and the lower edge of the other slot formed with teeth 2 2, the inner end of the slot at the outer end of the bracket terminating in a recess 3 below the lower edge of the slot, while the inner end of the slot at the inner end of the bracket terminates in a recess 4 above the lower edge of said slot. A screw or nail 5 fastens the bracket in each slot, the width of the slots being a little greater than the screw or nail shanks to allow the bracket to be freely slid 65 on and over them in adjusting and setting them to the length of the shade-roller, while the recess at the end of each slot so enlarges it that it allows the bracket to be removed over the heads of the fastening-screws when 70 the bracket has been moved outward to its limit to cause the recesses to register with the screw-heads, as in Fig. 4. In the upward tilting of the bracket it will be noted that its fastening-screw of the outer slot 75 will serve as the fulcrum on which the bracket is rocked to depress its inner end, as in Fig. 3, to allow it to be slid.

Another feature of novelty is the placing of the teeth on the lower edge of the inner slot 80 so that they will be caused to bite into the screw-shank, and thus effect a double security of the bracket against endwise movement when set. It will be understood that the bracket for the other end of the roller is 85 of identical construction and fastened in the same way, and that the teeth are made sharp to bite into the metal shanks of the fastening nails or screws, and that the weight on the bearing end of the bracket has the effect 90 of constantly tending to lift the inner end of the bracket, and thereby maintains the engagement of the teeth on the lower edge of the inner slot with the under side of the fastening-screw and the upper teeth of the 95 outer slot in engagement with the upper side of the fastening-screw.

I claim—

1. As a new article of manufacture, a shade-roller bracket, formed of a single piece 100 of sheet metal having an angle end for the roller-bearing, a pair of slots in alinement, the slot at the angle end terminating at its inner end in a recess at its lower edge, and having its upper edge formed with teeth, the 105 other slot terminating at its inner end in a recess at its upper edge and having its lower edge formed with teeth.

2. As a new article of manufacture, a shade-roller bracket formed of a single piece of sheet metal having an angle end for the roller-bearing, a pair of slots in alinement the 5 slot at the angle end having teeth on its upper edge and the slot at the inner end of the bracket having teeth on its lower edge.

In testimony whereof I have signed my name to this specification in the presence of two subscribing witnesses.

THEODORE THISTLEWOOD.
